UNITED STATES PATENT OFFICE.

GEORGE FRANCIS FISCHER, OF ROCHESTER, NEW YORK.

HEEL ATTACHMENT FOR BOOTS OR SHOES.

SPECIFICATION forming part of Letters Patent No. 769,157, dated September 6, 1904.

Application filed June 27, 1903. Serial No. 163,395. (No model.)

To all whom it may concern:

Be it known that I, GEORGE FRANCIS FISCHER, a citizen of the United States, residing at Rochester, in the county of Monroe and State of New York, have invented new and useful Improvements in Heel Attachments for Boots or Shoes, of which the following is a specification.

This invention relates to shoes, boots, and the like; and the object in view is to provide what may be termed a "reversible" double or half heel which by the special means hereinafter described may be quickly and readily applied to and removed from the heel portion of the sole and reversed at will.

The invention has special reference to the means whereby the heel is secured to the sole and made reversible, so that either surface of the heel may be presented for wear.

With the above and other objects in view, the nature of which will more fully appear as the description proceeds, the invention consists in the novel construction, combination, and arrangement of parts, as hereinafter fully described, illustrated, and claimed.

In the accompanying drawings, Figure 1 is perspective view of the shank and heel portion of a shoe-sole, showing the reversible heel applied thereto. Fig. 2 is a similar view minus the reversible heel. Fig. 3 is a detail perspective view of the reversible heel. Fig. 4 is a vertical longitudinal section through the heel, showing the connection of the same with the shank and heel portion of the sole. Fig. 5 is a similar view showing modified means for securing the heel in place. Fig. 6 is a detail perspective view of the band and its attachments by means of which the heel is secured to the sole in a manner shown in Fig. 5. Fig. 7 is a vertical longitudinal section similar to Fig. 4, showing the use of a heel-plate for positioning and securing the heel member to the sole. Fig. 8 is a detail perspective view of the heel-plate shown in Fig. 7. Fig. 9 is a detail section showing the manner of securing the clip to the sole where the stiffener-plate is embedded in the sole.

Like reference-numerals designate corresponding parts in all the figures of the drawings.

Referring to the drawings, 1 designates the shank of the sole of a boot or shoe, and 2 the heel portion, which is, by preference, made somewhat thicker than the shank 1, thereby forming the downwardly-extending shoulder 55 3, which when the heel is applied lies flush with the forward surface or edge thereof, as shown in Fig. 1.

In carrying out the present invention in its preferred embodiment I make use of a band 60 4, preferably of leather or rubber, but which may also be formed of metal or other material. This band is secured along its upper edge to the periphery or outer edge of the heel portion of the shank, as shown in Figs. 65 1 and 2, and extends below the lower surface of the heel portion 2, where it is beveled or chamfered along its inner surface, as shown at 5, to correspond with the bevel or chamfer of the heel proper, which is shown at 6. 70

The heel 6 is of a size adapting it to fit against the lower surface of the heel portion 2 of the shank and is reversely beveled along its periphery or outer edge, as shown at 7, so as to fit snugly within the pendent portion of 75 the band 4, as shown in Fig. 1, and also to provide for reversing the heel, or, in other words, turning the same upside down.

The heel may be made of leather, rubber, or other material and is provided with a centrally-located mortise or recess 8, opening out at the front of the heel and in which is inserted a core or stiffener 9, preferably of wood or metal, said core extending well back to the rear edge of the heel, as shown in Fig. 80 5. In its forward edge the core 9 is provided with a socket 10, which receives the rearwardly-extending lower lip or terminal 11 of a three-sided or U-shaped heel fastener or clip 12, which is also provided with the upper 85 and inwardly extending lip or terminal 13, which is inserted in the mortise or recess 14 in the thickened part 3 of the heel portion 2 of the shank, as shown in Fig. 4. In this way the forward portion of the heel is securely 90 anchored to the sole. 95

The heel is further provided with a hole 14, extending therethrough from top to bottom and having the end portions thereof enlarged or countersunk, as shown at 15, to form suc- 100

tion-holes and to receive the head of a screw 16, which is inserted into the heel portion of the shank, as shown in Fig. 4, thereby firmly securing the heel to the sole. The head of 5 the screw 16 bears against the shoulder formed by countersinking the edges of opening 14, while the core 9 takes the pressure of the head of the screw and prevents the mutilation or destruction of the heel. By removing 10 the screw 16 and the clip 12 the heel may be removed, reversed, and reapplied, thus increasing the life of the heel, and consequently the shoe.

If desired, the band 4^a may be provided 15 along its inner surface with a series of heel-fasteners 17 in the form of double-pronged clips, each clip comprising a pair of prongs 18, arranged one above the other, as shown in Fig. 6. These clips are secured firmly to 20 the band 4^a and are adapted to be driven into the heel, so that one prong of each clip will enter the heel, thereby firmly securing the heel to the sole. Additional prongs 19 may also be secured to the extremities of the band 25 4^a, as shown in Fig. 6, and be driven into the forward surface or edge of the heel. Where the band 4^a is made of leather or analogous material, metal clips or prongs may be secured thereto in any convenient manner. If 30 the band 4^a is made of metal, however, or metal covered with leather, the prongs 18 and 19 may be formed integrally with said metal band.

Where the band 4^b is composed of metal or 35 hard rubber, it may be connected with what I term a "heel-plate" 20, as shown in Figs. 7 and 8, the band forming a pendent flange of said heel-plate and being adapted to receive the upper portion of the reversely-beveled 40 heel. Under the arrangement just referred to the heel-plate 20 will be provided with holes 21 to receive fasteners, by means of which said plate, together with its rim or band 4^b, is secured to the heel portion of the sole, 45 as shown in Fig. 7.

Instead of connecting the clip 12 with the sole in the manner shown in Fig. 4 it may be connected to a stiffener-plate 22, where such a plate is located and embedded in the sole, as 50 shown in Fig. 9. In such a case the clip will have its upper portion bent, as shown at 23, and riveted to the stiffener-plate 22. The clip 12 is formed of spring metal, so that it will give or yield in applying and removing 55 the heel.

By means of the construction hereinabove described it will be seen that a new heel may be readily applied to a shoe at any time without the use of nails, screws, or other usual fastening devices and that said heel may when partially worn out be reversed, so as to present a new wearing-surface, thus adding materially to the life and durability of the shoe as a whole. The heel may be made of any size or thickness, and other changes in the form, 60 proportion, and minor details of construction may be resorted to without departing from the principle or sacrificing any of the advantages of this invention.

Having thus described the invention, I claim 70 as new—

1. The combination with the heel portion of the sole, of a heel constructed from its inner edge with a mortise having a core inserted therein, a screw for securing the heel to said heel portion, and means connecting the inner edge of the core with the sole, said core receiving the pressure of the head of the screw. 75

2. The combination with the heel portion of the sole, of a heel having a central opening and constructed with a mortise having a core inserted therein, a screw adapted to said opening for securing the heel to said heel portion, and a clip connecting the core with the sole, said core receiving the pressure of the head 80 of the screw.

3. The combination with a sole, of a heel, a band connected with the sole and embracing the heel, and a clip having portions which engage the heel and the heel portion of the sole, 85 substantially as described.

4. The combination with a sole, of a heel, a band connected with the sole and extending around the heel, a core embedded in the heel, a clip connecting the core and sole at the 90 front of the heel, and a screw passing through the core and engaging the heel portion of the sole, substantially as described.

5. The combination with a sole, of a heel, a band connected with the sole and embracing the heel, a core embedded in the heel, and a clip having lips inserted in the core and in the 95 heel portion of the sole.

In testimony whereof I affix my signature in presence of two witnesses.

GEORGE FRANCIS FISCHER.
